DOME-SHAPED LAWN SPRINKLER

Gray L. Butler, Waterbury, Conn., assignor to Scovill Manufacturing Company, Waterbury, Conn., a corporation of Connecticut

Application October 26, 1946, Serial No. 705,832

1 Claim. (Cl. 299—56)

1
This invention relates to lawn sprinklers and particularly to a simple type of dome shaped lawn sprinkler having no movable parts.

It is the principal object of this invention to make all the parts that go into the construction of the sprinkler unit from drawn up sheet metal members and designing such parts so that the fluid is directed laterally into a dome shaped chamber and discharged out through an apical hole in the form of a relatively fine spray. In the use of sheet metal for constructing the individual parts further thought is given to the particular construction of each member and the manner in which they are assembled in order to perfect a lawn sprinkler of very simple construction, strength, efficiency and also one of attractive appearances.

A further object is to provide a sprinkler unit of the above character having a swivel nut as one of its members so that the sprinkler unit as a whole can be adjustable relative to the end of the hose.

With these objects in view and others not specifically referred to, the invention consists in the features, combinations, details of construction and arrangements of parts which will first be described in connection with the accompanying drawing and then more particularly pointed out.

In the drawing:

Fig. 1 shows a side elevational view of a sprinkler unit as attached to the end of a hose.

Fig. 2 is a vertical sectional view through the sprinkler as detached from the hose and taken on a plane through the axis of the intake nozzle.

Fig. 3 is a sectional view taken on line 3—3 of Fig. 2 looking in the direction of the arrows, and

Fig. 4 is a perspective view of the cup shaped nozzle, per se.

In considering now a description of the parts the numeral 10 refers to a dome shaped housing shell made of relatively thin metal and approaching almost a hemisphere of hollow construction. The open end of this shell is enlarged relative to the diametrical surface of the housing shell as at 11 with a connecting shoulder 12 therebetween. The enlarged section 11 initially projects downwardly as shown at 11a in dotted outline in Fig. 2.

To close the open end of the housing shell 10 a closure base or disc 13 is provided and the main portion 14 of this closure base is of a relatively large spherical dished shape to give it strength for the purpose of strengthening the

5 sprinkler construction in general and also to withstand the internal water pressures to which it may be subjected when the sprinkler is in use. The closure base at the peripheral edge of the dish shaped portion 14 is provided with a substantially cylindrical wall 15 that telescopically fits into the open end of the housing shell 10.

10 The end of this cylindrical wall is formed with an outward flange 16 that abuts against the shoulder 12 as a stop when the closure disc 13 is assembled in position. When thus assembled the depending portion 11a of the enlarged section 11 will be closed over as at 17 to permanently assemble the closure base 13 into the housing shell 10.

15 Positioned a short distance above the base of the housing shell is an opening 18 in the side wall thereof, and surrounding this opening is an 20 outwardly drifted annular ring or cylindrical neck 19 constructed to have its axis normal to the vertical axis of the sprinkler and parallel to the base of the same. A cup shaped nozzle shell 20 is fitted into the cylindrical neck 19 by a 25 relatively tight fit and preferably is permanently secured as by a ring of solder as shown at 21 in Fig. 2 for the purpose of preventing leakage at this point. The open and outer end of the nozzle shell is formed with an integral outward flange 22. Prior to the assembly of the nozzle shell 20 to the cylindrical neck 19 a swivel nut 23 of conventional construction is telescoped over the shell 20 and is swively abutted against the flange 22. The usual form of washer, not shown, 30 may be inserted into the swivel nut to rest against the flange 22. The swivel nut is employed to make the usual detachable connection between the male nipple 24 usually provided on one end of a garden hose 25 such as shown in Fig. 1.

35 In order to set up the right swirling action within the domed housing 10 and break up the water into a relatively fine spray as it is discharged through the opening 10a, the closed or base end 26 of the nozzle shell may be considered 40 a baffle plate. Formed in this base end 26 is a progressively increasing conical section 27 formed inwardly relative to the shell 10 and the enlarged end of this conical section 27 is slit and forced outwardly relative to the base end 26 to provide 45 a relatively large lateral discharge opening 28. The base end 26 including the conical section 27 provides a substantially abrupt stop to the water being directed in through the nozzle shell 20, and with the pressure resulting in the fluid a considerable head will be formed to force the water

through the lateral opening 28 with considerable velocity. The opening 28, as best seen in Fig. 2, is relatively close to the inner spherical wall of the domed shell 10, so that the water directed into the housing 10 will travel around in a circular manner and, it is presumed, will more or less fill up the hollow portion or chamber within the housing 10 and progressively fill up the chamber from the base upwardly. The fact that the housing is dome shaped with the discharge opening 10a at the apex, the chamber in the housing 10 becomes progressively decreasing in size as it leads up to said opening 10a and consequently the angular velocity of the circulating water as it rises within the chamber will increase in speed and be discharged from the opening in a rapid swirling manner of a character to break up the stream of water into a relatively fine spray most desirable for the sprinkling of lawns.

It is, of course, obvious that minor changes in details of construction and arrangement of parts may be made without departing from the scope of the present invention as set forth in the appended claim.

I claim:

A sprinkler comprising a hollow body member of substantially semi-spherical shape, a base closing the open end of said body member, said body member having a central opening for discharging water in an upward direction, a cylindrical neck portion extending outwardly and horizontally from the body member adjacent the base, a cup-shaped nozzle shell having a closed end and a cylindrical wall, said nozzle shell fixed in said neck with the upper junction point of said

5

shell wall and closed end being located at the inner surface of said body member and the major portion of said shell projecting outwardly from said body member, the end wall of said nozzle shell having a straight vertical slit with a portion of said end wall on one side of said slit being formed inwardly into said body member to provide a horizontally extending conical shaped channel deflector which increases in size toward the slit for directing water laterally at the inner end of said nozzle shell into said body member adjacent the lower part of the wall of the semi-spherical body member whereby the water is caused to flow within said body member with a whirling motion toward the discharge opening, and means for coupling said nozzle shell to a garden hose.
